[57] CLAIM

The ornamental design for scissors, as shown and de-
scribed.

DESCRIPTION

FIG. 1 is a perspective view of the scissors showing my
new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a top plan view thereof; and

FIG. 8 is a fragmentary rear elevational view of an
alternate embodiment of FIG. 1, the position of the
notch in the blade being the only difference.

FIG. 1

FIG. 6
